UNITED STATES PATENT OFFICE.

GEORGE W. PUTNAM, OF GLENS FALLS, ASSIGNOR TO ROBERT C. BLACKALL
AND CHARLES D. HAMMOND, OF ALBANY, N. Y.; ONE-THIRD TO EACH.

CAR-COUPING.

SPECIFICATION forming part of Letters Patent No. 228,675, dated June 8, 1880.

Application filed March 25, 1880. (No model.)

To all whom it may concern:

Be it known that I, GEORGE W. PUTNAM, of Glens Falls, in the county of Warren, and in the State of New York, have invented certain new and useful Improvements in Car-Couplings; and I do hereby declare that the following is a full, clear, and exact description thereof, reference being had to the accompanying drawings, and to the letters of reference marked thereon, making a part of this specification.

The nature of my invention consists in the construction and arrangement of a car-coupling, as will be hereinafter more fully set forth.

In order to enable others skilled in the art to which my invention appertains to make and use the same, I will now proceed to describe its construction and operation, referring to the annexed drawings, in which—

Figure 1 is a side view of my improved car-coupling. Fig. 2 is a longitudinal vertical section of the same; and Fig. 3 is a plan view with the cap and coupling-pin removed.

A represents the draw-head, provided with the mouth B and interior chamber, C. In the top of the draw-head is an opening for the insertion of the hook or coupling-pin D, which is formed with a curved arm, F. This arm extends into the bottom of the draw-head, and is there pivoted by a pin or bolt, a, below the

link. The hook D is formed with a shoulder, b, at the front, and its rear is rounded and serves as a pin for coupling in an ordinary link. The front of the hook is inclined back from the shoulder to the cap G, the opening of the draw-head being made to correspond. The cap G is sufficiently large to cover the opening in the top of the draw-head, and it forms

a square shoulder, d, against a shoulder, e, in the head, so that all strain is taken off from the arm F and the bolt a, the bolt-hole being made large enough to allow the hook to slide into place and draw on the head.

In a recess at one side of the draw-head is pivoted a lever, I, which has a shoulder, i, that comes under the edge of the cap, for the purpose of uncoupling; or it can be uncoupled by means of a cord tied to a staple, h, on the cap.

In operation for coupling, the link strikes the hook, when the same will slide back as far as the elongated hole x in the arm F will permit, and then it rises up, allowing the link to pass, and falls back into place.

Having thus fully described my invention, what I claim as new, and desire to secure by Letters Patent, is—

1. The pivoted lever I, having shoulder i, in combination with the draw-head A and hook D, with cap G, substantially as and for the purposes herein set forth.

2. The combination of the draw-head A, having opening in the top, the coupling-pin D, formed, with the cap G and curved arm F, in one piece, and having the end of said arm pivoted in the bottom of the draw-head below the line of the link, and the shouldered lever I, all constructed substantially as and for the purposes herein set forth.

In testimony that I claim the foregoing I have hereunto set my hand this 5th day of March, 1880.

GEO. W. PUTNAM.
